UNITED STATES PATENT OFFICE.

NOAH A. AREL, OF TULSA, OKLAHOMA.

DANGER-SIGNAL.

1,300,104.

Specification of Letters Patent.

Patented Apr. 8, 1919.

Application filed October 29, 1918. Serial No. 260,182.

To all whom it may concern:

Be it known that I, NOAH A. AREL, a citizen of the United States, residing at Tulsa, in the county of Tulsa and State of Oklahoma, have invented new and useful Improvements in Danger-Signals, of which the following is a specification.

This invention relates to automatic signals for railroad crossings and the like and the principal object of the invention is to provide mechanical means operated by the train for displaying a signal at the crossing to indicate that a train is coming.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a plan view of my invention. Fig. 2 is a side view with parts in section. Figs. 3 and 4 are detailed views.

Fig. 5 is a cross section through the upright and shaft showing the means for holding the parts in inoperative position.

In these views 1 indicates the track and 2 the crossing. Adjacent the crossing I locate an upright 3 suitably supported on a base 4. The upright 3 is of tubular form and the shaft 5 passes therethrough. The end of the shaft is provided with a crank 6 and its upper end projects above the upright and has secured thereon an arm 7 which contains the legend "Stop—Danger" or similar words. A pair of shields 8 is also secured to said shaft at its upper end and a lamp 9 is placed between said shields and is suitably secured to the upright 3. A wheel 10 is rotatably mounted at the upper end of the upright 3. This wheel is supplied with ball bearings so that it will revolve by its own momentum after being started. The wheel is provided with the annular rack 11 which is engaged by the dog 12 carried by the

shaft. The wheel also carries a number of strikers 13 which are adapted to contact with a bell 14 carried by the upright. The upright may be braced by the ladders 15.

The crank 6 is connected with a pair of 60 sliding rods 16 by the chains 17. These chains pass over the guiding rollers 18. The rods 16 are suitably mounted along the track and extend in opposite directions. Each rod is connected with an oscillating 65 member 19, which is pivoted intermediate its ends at a suitable point along the track so that it will be struck by a part carried by the train. This will cause the rod to slide and through means of the chain 17 will partially rotate the crank and thus turn the shaft so as to place the words on the arm in a position where they may be seen by anyone passing along the crossing 2. At the same time the dog engaging the rack will 75 spin the wheel 10 and thus sound the alarm. The shields 8 will be moved so as to expose the lamp, so that a signal may be given at night. The parts are returned to normal position after the train has passed by means 80 of the weighted arms 20 connected with the chains and the weight 21 connected with the arm 6. This weight 21 is connected with the arm by a cable which passes over a suitable roller. It will be seen that one rod will not 85 interfere with the other as the chains will simply slack while one rod is being moved.

It is thought from the foregoing description that the advantages and novel features of my invention will be readily apparent. 90

I desire it to be understood that I may make changes in the construction and in the combination and arrangement of the several parts, provided that such changes fall within the scope of the appended claim. 95

What I claim is:—

A device of the class described comprising an upright, a shaft rotatably supported thereby, signal means carried by the shaft, a wheel rotatably carried by the upright, 100 strikers on said wheel, an annular rack on said wheel, a dog on the shaft engaging said rack, a bell on the upright adapted to be engaged by the strikers, a trip device located adjacent the track and adapted to be struck 105 by part of the train and means for connecting said device with the shaft.

In testimony whereof I affix my signature.

NOAH A. AREL.
